UNITED STATES PATENT OFFICE

WALTER O. GORR, OF NEW YORK, N. Y., ASSIGNOR TO W. W. HARTS, JR., AND C. B. HARTS, BOTH OF NEW YORK, N. Y.

STENCIL HAND STAMP

Application filed October 20, 1928, Serial No. 313,814. Renewed October 24, 1930.

The present improvement in stencil hand stamps or duplicators relates particularly to improvements in the construction of the inking pad and stencil which are stretched over the foraminous bottom wall of the hollow stamp body and to the means for detachably mounting the pad and stencil upon the body of the stamp. Ink pads and stencil sheets are both provided with reinforced opposite ends made by attaching two-ply folded reinforcing strips having strengthening steel wires enclosed in the folds of the reinforcing strips, suitable perforations or openings being cut through the reinforcing strips just inside of the wired folded edges, to provide strong holes or openings to fit over suitable lugs or pins carried by the stamp body. The construction of the inking pad and the stencil is substantially the same with regard to the reinforcement of the edges, the material from which the pad and stencil are formed being, of course, quite different because of the different requirements.

The hand stamp is formed of a hollow body having a segmental cylindrical bottom wall which is perforated throughout its area excepting at its edges where the bottom wall is attached by soldering or brazing to the side and end walls of the hollow body. Projecting from one of the body side walls are the headed pins or studs with which the holes or openings at one edge of the inking pad and the stencil are engaged, while at the opposite side of the stamp body there is provided an adjustable tension bar consisting preferably of an angle bar fitting the upper corner and side of the stamp body, said tension bar carrying a plurality of outwardly-presented pins or lugs with which the holes or openings in the opposite edges of the inking pad and stencil sheet are engaged. This tension bar slides upon two or more headed pins or studs projecting upwardly from the top of the stamp body, the bar being perforated to fit loosely upon the guide pins or studs and provided between said guides with some form of hand-operated device for raising the tension bar upon the stamp body to apply stretching tension to the pad and stencil which projects over the foraminous body wall.

The hollow stamp body is preferably formed with a removable cover plate snugly fitting an opening of substantial size in the top, the cover plate carrying the handle which preferably carries some form of latch to secure the cover plate and handle to the top of the stamp body.

An important feature from a practical standpoint of the improved stencil hand stamp is the fact that the hollow body is formed with imperforate side and end walls and a considerable imperforate portion of the top wall so that when a surplus quantity of ink is supplied to the hollow body and it is desired to place the stamp aside temporarily while it is not in use, it can be put in inclined position resting upon either end or either long side and the handle, without danger of the surplus ink running out and soiling the table or other support.

In order that the invention will be fully understood, it will first be described with reference to the accompanying drawings and afterwards more particularly pointed out in the annexed claims.

In said drawings:

Figure 1 is a top perspective view of the improved stencil hand stamp.

Figure 2 is a detached view of an improved inking pad, partly broken away.

Figure 3 is a detached view of the improved stencil sheet, parts being broken away.

Figure 4 is a vertical longitudinal sectional view of the improved hand stamp.

Figure 5 is a vertical transverse sectional view of the same.

Figure 6 is a detail sectional view of parts of the same, showing the shifted position of the pad and stencil tension bar.

Figure 7 is a detail sectional view taken on the line 7—7 of Figure 6.

Figure 8 is a detail sectional view similar to Figure 5, but taken through the adjusting screw of the tension bar.

The hollow body of the improved stencil hand stamp is formed of a top plate 1 having the integral downwardly presented side flanges 2 extending at right angles to the top plate and to which the opposite edges of the segmental cylindrical bottom wall 3 are

brazed or soldered. The bottom wall 3 is closely perforated throughout the greater part of its area. The hollow body is completed by the two end wall sections 4 which 5 are brazed or soldered to the flanged top plate 1 and the foraminous bottom wall 3. In this way the hollow body with the perforated bottom wall is provided with imperforate side and end walls and part of the 10 top wall so that when the body is inverted and placed over in angular position resting partly on the handle (hereinafter referred to), there will be an imperforate angular pocket to hold any surplus ink and prevent 15 its flowing out through the bottom wall to spread upon the table or other support. The top wall 1 has a relatively large central rectangular opening 5 cut through it, in which closely fits a removable cover plate 6 resting 20 preferably upon a flange or stop plate 7 secured to the inner surface of the top plate 1, and projecting slightly within the cover opening 5 to provide a ledge for the support of the cover plate 6. The cover plate 6 has 25 rotatably mounted upon it a handle 8 secured by means of a bolt or screw 9 inserted from beneath and passing through a locking bar 10 which is keyed or otherwise fastened to the bolt or screw 9 so as to rotate upon the cover 30 plate 6 with the handle 8. Spacing washers 11 and 12 are mounted between the locking bar 10 and cover plate and between the handle 8 and cover plate for the purpose of giving the handle and locking bar more freedom 35 of movement. It will be observed that when the cover plate 6 is mounted in the opening 5 of top plate 1, as shown particularly in Figure 5 of the drawings, the handle 8 can be turned to move the locking bar 10 from 40 its unlocked position parallel with the longitudinal axis of the stamp body into its locked position transverse to the stamp body in which position it will engage beneath the flange or stop plate 7 and lock the cover plate 45 in the opening of the top plate and at the same time firmly support the handle 8 upon the stamp body in readiness for use.

These duplicators or stencil stamps are commonly formed with perforated bottom 50 walls and ink pads and stencil sheets extending over the perforated bottom wall with means for holding the pad and stencil in position.

In the improved stencil hand stamp both 55 the ink pad and the stencil are formed with specially reinforced edges for the engagement of securing means upon the stamp body, the reinforcements being not only for strength to withstand the usual handling of 60 these parts but in the present case to stand the stretching tension to which they are subjected by the adjustable securing means upon the stamp body.

15 is the ink pad made of a sheet of proper 65 material such as usually employed, to the op-

posite edges of which are stitched at 19 the two-ply folded strengthening strips 16 of linen or other material of suitable strength. Enclosed in the fold of each of the folded strips 16 is a small steel wire 17 to add great 70 strength to the edges of the pad. Along each strengthened edge of the ink pad suitable perforations or openings 18 are punched for the reception of the studs or lugs upon the stamp body presently to be referred to.

In Figure 3 is shown a stencil sheet made of suitable stencil material indicated at 20. This stencil sheet 20 is mounted upon a temporary backing sheet 21 of tough paper, the edges of the backing sheet 21 being folded over at 22 to enclose the edges of the superposed stencil sheet 20. The folded-over edges of sheet 21 and the edges of stencil sheet 20 are permanently secured together by glue or cement and are also stitched along the lines indicated at 23. Strengthening wires 24 are enclosed within the folds at the edges of sheet 21 and suitable holes or openings 25 are punched through the superposed stencil sheet 20 and folded-over strengthening edge of the tough paper sheet 21. This supporting paper sheet 21 has indicating longitudinal lines 21a, 21b and 21c and the transverse lines 21d and 21e printed upon its face against which the stencil sheet 20 is mounted, said printed lines indicating the central zone and the top and bottom and side limits within which matter may be written or printed upon the stencil. The stencils are preferably prepared in an ordinary typewriting machine, the reinforcement and the top and bottom edges of the stencil and reinforcing sheet being such as to readily pass through the typewriting machine.

Returning to consideration of the body of the stencil hand stamp, it will be observed that one of the longitudinal side walls 2 is provided with outwardly projecting head pins or lugs 30, four of them being employed on a large size stamp. These headed pins or lugs 30 are spaced to correspond with the spacing between the perforations or openings 18 of the pad 15 and 25 of the stencil 20 so that one edge of the pad and one edge of the stencil can be mounted upon these headed pins or lugs, the stencil being superposed upon the pad.

At the opposite side of the stencil body, the top plate 1 has projecting up from it two headed guide pins 35 over which fit the perforations 36 of the angular tension bar 37. Projecting from the side of the angle bar 37 are the four spaced headed pins or lugs 38 corresponding in position and spacing to the pins or lugs 30 above referred to.

When the pad 15 and stencil 20 are engaged at one edge upon the pins 30, they are carefully smoothed over the surface of the foraminous bottom plate until their opposite perforated 120 125

strengthened edges are brought alongside of the headed pins or lugs 38 of the tension bar 37 and the perforations of the pad and stencil slipped over said headed pins or lugs 38. In applying the pad and stencil, the body member is rolled from the edge supporting pins 30 toward the edge carrying the tension bar 37. It is preferably to disconnect the edge of the protecting sheet 21 from the folded reinforced edge of the stencil prior to placing the perforations of the stencil over the headed pins 38, although this breaking away of the protecting sheet may be done later. After the stencil is properly engaged upon the pins of the tension bar 37, the protecting sheet is torn from its opposite edge so as to expose the stencil sheet. This tough paper sheet 21 can readily be torn off because of the perforations caused by the stitching. This removal of the protecting tough paper sheet may also be facilitated by further cutting it along the lines of desired separation.

The tension bar 37 is provided with a thumb screw 40 threaded through the bar 37 and engaging the top plate 1 of the stamp body. After the pad and stencil are properly placed over the perforated bottom plate with their reinforced edges engaged upon the pins 30 and 38, the tension bar 37 is placed under tension by screwing down the thumb screw 40 with the result indicated in Figures 1, 6 and 7 of uniformly stretching the pad and stencil over the perforated bottom plate. The length of the headed guide pins 35 is just sufficient to permit a proper stretching of the pad and stencil. The heads of these pins 35 limit the stretching movement of the plate 37 so that an inexperienced operator cannot over-strain the stencil. When the pad is saturated with stencilling ink, it will be found that the stencil stretches easily and uniformly over the surface of the pad. Any suitable means may be provided for adjusting the position of the tension bar 37 upon the body of the stencil stamp.

In changing stencils, it will be understood that the adjusting screw 40 is loosened up so that the tension upon the stencil is released. The stencil can then be removed from engagement with the pins 30 and 38 and a new stencil put in place and the tension bar again adjusted for stretching the new stencil. In this changing of stencils it will be found that the ink pad remains unchanged in its position because the material of the pad is forced more or less into the interstices of the foraminous bottom plate so that the pad in effect interlocks with the bottom plate and does not readily shift in the operation of taking off a stencil and putting a new one on. When it becomes necessary to renew the inking pad, it can, however, be readily taken off of the supporting pins 30 and 38 and a new pad put in its place. The stencil stamp may be inked by removing the cover plate 6 and pouring

a sufficient quantity of suitable stencilling ink into the chamber of the stencil body. If a limited number of impressions is to be taken, satisfactory results can be obtained by painting the ink upon the inner surface of the perforated bottom plate, a suitable brush for this purpose being operated through the opening in the top plate 1. In the usual manner, ink spreads through the perforations of the bottom plate to the ink pad, which uniformly spreads the ink beneath the stencil. Impressions are made by simply rolling the hand stamp over the surface upon which the print is to be made, the handle 8 being convenient for this operation.

The stencil hand stamp may be conveniently kept when not in use in the usual shallow tray although because of the imperforate parts of the side end and top walls of the hollow body, it can be inverted and placed in inclined position resting upon the handle and one of the side or end edges without danger of ink leaking through and soiling the table or other support.

I claim:

1. A stencil hand stamp comprising a hollow body having a foraminous bottom wall, and imperforate top, side and end walls, said top wall having a covered opening spaced from the imperforate sides and ends, and the detachably mounted ink pad and stencil sheet extending over said foraminous bottom wall, said imperforate wall portions forming ink retaining pockets when the stamp is in inverted inclined position.

2. A stencil hand stamp comprising a hollow body having a foraminous bottom wall, imperforate end walls, and a top having depending flanges forming sides and an opening spaced from the ends and sides, a cover plate fitting said top opening, a handle movably mounted upon said cover plate, a cover locking device connected with and actuated by said handle, and the ink pad and stencil sheet extending over said foraminous bottom wall.

3. A stencil hand stamp comprising a hollow body having a foraminous bottom plate supporting an ink pad and a stencil sheet, a top wall having a central opening formed with a cover-receiving seat, a cover plate fitting said seat, a handle movably mounted upon and supported by said cover plate, and a locking member connected with said handle and adapted to engage said seat adjacent to said opening for securing said cover plate upon its seat and supporting said handle upon the hollow body.

4. In a stencil hand stamp, the combination with a hollow body having a foraminous bottom plate, stencil securing means, and an inking pad extending over said foraminous plate, with a stencil comprising a sheet of suitable stencil material and a protecting backing sheet secured along two of its edges

to said sheet of stencil material, said backing bar, and means for adjusting said tension bar upon said guide pins.

5. In a stencil hand stamp, the combination with a hollow body having a foraminous bottom plate, stencil securing means, and an inking pad extending over said foraminous plate, with a stencil comprising a sheet of suitable stencil material and a protecting backing sheet having two of its edges secured to edges of the sheet of stencil material, said backing sheet being formed with weakened lines adjacent to its two secured edges to facilitate tearing away and removing said backing sheet.

15 6. A stencil for duplicating hand stamps, comprising a sheet of suitable stencil material, a protecting backing sheet having its reinforcing edges folded over and secured to the edges of the sheet of stencil material, and weakened lines in said backing sheet adjacent to said reinforcing folded edges to facilitate tearing away and removing said backing sheet from the folded edge strips.

25 7. A stencil for duplicating hand stamps, comprising a sheet of suitable stencil material, a protecting backing sheet having its reinforcing edges folded over and secured to the edges of the sheet of stencil material, said folded edges carrying concealed reinforcing wires and having holes or openings punched therein, and weakened lines in said backing sheet adjacent to said reinforcing folded edges to facilitate tearing away and removing said backing sheet from the folded edge strips.

40 8. A stencil for duplicating hand stamps, comprising a sheet of suitable stencil material, a protecting backing sheet having its reinforcing edges folded over and secured to the edges of the sheet of stencil material, and weakened lines in said backing sheet adjacent to said reinforcing folded edges to facilitate tearing away and removing said backing sheet from the folded edge strips, said backing sheet having upon its face next to the stencil sheet suitable indication of the limitations and division of the available stencil area.

50 9. In a stencil hand stamp, the combination with a hollow body having a foraminous bottom plate, sheet-engaging lugs upon one side of said body, a tension member movably mounted upon the opposite side of said body, sheet-engaging lugs upon said tension member, and means for adjusting said tension member.

60 10. In a stencil hand stamp, the combination with a hollow body having a foraminous bottom plate, pins or lugs upon one side of said body, a tension bar upon the opposite side of said body, guide pins projecting from said body through guide openings in said tension bar, pins or lugs upon said tension

70 11. In a stencil hand stamp, the combination of a stamp body, the headed pins or lugs upon one side of said body, guide pins upon the opposite side of said body, an angular tension bar formed with guide openings engaging said guide pins, headed pins or lugs upon said tension bar, and a hand operated tension screw controlling the adjustment of said tension bar upon said guide pins, the headed pins or lugs being adapted to engage the holes or openings in the opposite edges of a stencil.

75 12. A stencil for duplicators, comprising a sheet of suitable stencil material and a protecting backing sheet having two of its edges secured to and reinforcing the edges of the sheet of stencil material, said backing sheet being formed with weakened lines adjacent to its secured reinforcing edges to facilitate tearing away and removing said backing sheet from the stencil sheet.
